UNITED STATES PATENT OFFICE.

JOHN ALISON BUTTS, OF WADLEY, GEORGIA.

COTTON-CHOPPER.

SPECIFICATION forming part of Letters Patent No. 781,399, dated January 31, 1905.

Application filed October 13, 1904. Serial No. 228,291.

To all whom it may concern:

Be it known that I, JOHN ALISON BUTTS, a citizen of the United States, residing at Wadley, in the county of Jefferson and State of Georgia, have invented certain new and useful Improvements in Cotton-Choppers; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and useful improvements in cotton-choppers; and it has for its object, among others, the provision of a simple, inexpensive, and serviceable machine of this character involving a construction in which the cutting-blade is positioned between the driving-wheels and in advance of the seat of the operator, so that the operation of the cutting-blade is at all times visible and its guidance readily controlled by the operator. A guide-wheel is provided in advance of and in the direct line of travel of the cutting-blade, this wheel serving to indicate at all times the direct line of the chopper.

The invention further resides in the provision of a lever-actuated mechanism for throwing the chopping-blade into and out of service and also in the provision of mechanism whereby the chopper may be raised or lowered, as desired, in order to escape stones or other obstructions.

The invention is clearly illustrated in the accompanying drawings, which, with the letters of reference marked thereon, form a part of this specification, and in which—

Figure 1 is a central vertical longitudinal section taken through a cotton-chopper constructed in accordance with my invention. Fig. 2 is a front elevation. Fig. 3 is a top plan view, and Fig. 4 is a rear elevation, of the same. Fig. 5 is a perspective view of my invention, portions of the sleeves being broken away.

Reference now being had to the details of the drawings by letter, A A represent the driving-wheels of the machine, which are jour-

naled upon the curved axle B, and a seat C is secured to the free end of a yielding metallic strip C', the forward end of which is securely bolted to the rear portion of the frame D.

E is a guide-wheel which is journaled in the bifurcated lower end of a support E', the upper end of which is bolted or otherwise suitably secured to the forward end of the frame D. It will be noted that the said guide-wheel E is positioned at a point slightly to one side of the longitudinal center of the machine.

E² is a shaft journaled at its forward end in openings provided in bifurcated ends F' of a depending support F, said shaft having a bearing within a vertical slot or loop H and the said shaft having attached thereto a rotatable chopping-knife H'.

Between the bifurcated ends F' of the member F is provided a sprocket-wheel I, the said wheel being journaled upon the forward end of the shaft E², as shown. Around this sprocket-wheel I and around a sprocket-wheel K upon a longitudinal shaft K' is passed a sprocket-chain L, traveling over an idler T. Journaled upon the shaft K' is a beveled gear-wheel M, which meshes with a gear-wheel M', having a hub portion O' with a serrated edge designed to receive a movable clutch-collar O, which is moved longitudinally upon the axle by means of an angle-lever O², the lower end of said angle-lever being bifurcated, with two curved arms O³ connected at O² to said clutch-collar O, as clearly shown in Fig. 5 of the drawings. A lever N is mounted upon a pivot-pin N', carried by the bar N², which is secured to the frame of the apparatus, and said angle-lever O² is also pivotally connected upon the pin N', as shown clearly in Fig. 5 of the drawings, while the downwardly-extending end of the lever O² is pivotally connected at N³ with the lever N, whereby as said lever N is thrown in one direction or the other the clutch-collar O will be thrown into or out of engagement with the serrated hub O' upon the gear-wheel M'. 95

In order to raise and lower the shaft carrying the chopping-knife, I provide the following mechanism, comprising the upright posts P, which rise from the frame D and which posts are connected by a cross-piece P² 100

and suitably braced by the bars P^3 . Upon each of said posts is a sleeve P' , and P^4 designates a bar having a vertical play upon said posts and has its ends downwardly bent and 5 pivotally connected at P^5 to the links P^6 , the lower end of one of said links being pivotally connected to the angle-lever Q , mounted upon the frame of the machine. Mounted upon the frame is a notched segment Q^2 , and a pawl Q^X 10 is connected to rod Q^3 and is designed to engage the notch in said segment, while a hand-lever Q^4 , pivotally connected to the lever Q , has connection with said rod Q^3 . Depending from the bar P^4 is an arm P' , which is pivotally 15 connected to the upper end of the bar F . By this construction it will be observed that the shaft carrying the chopper may be raised or lowered by the simple manipulation of the lever mechanism shown and described.

20 From the foregoing description the operation of the device will be at once readily understood.

It will be seen that in use the seat is so positioned that the operator is directly above his 25 work and is within full view of all parts of the machine, the guide-wheel being in advance of and in line with the chopper or hoe and indicating at all times the line of travel of the hoe, so that the same may be maintained at the desired or proper distance from 30 the row of cotton under cultivation. By means of the lever mechanism for engaging and disengaging the clutch mechanism at one side of the machine the same may be thrown 35 out of gear very readily when it may be desired to move the machine from place to place

without imparting a rotary movement to the chopper or hoe.

Having thus described my invention, what I claim to be new, and desire to secure by Letters Patent, is—

40 A cotton-chopper comprising a frame, an axle and driving-wheels, a clutch-collar splined to the hub of one of said wheels, an angle-lever having a bifurcated end swiveled to 45 said clutch-collar, a gear-wheel journaled upon said axle and having a hub with serrations or teeth upon one edge thereof and adapted for engagement with said clutch-collar, a bevel gear-wheel and sprocket-wheel mounted upon 50 a suitable stub-shaft, a vertically-movable bar having its lower end bifurcated, a shaft journaled in the arms of the bifurcated end of said bar, a guide for the opposite end of said shaft carried by said bar, a sprocket-wheel fixed to 55 said shaft and mounted between the arms of the bifurcated end of the bar, a sprocket-chain connecting said sprocket-wheels, a chopper carried by said shaft, posts rising from the frame, a bar having angled ends mounted 60 upon said posts, a lever pivoted to the frame and having link connections with said angled bar, said bar carrying said shaft being pivotally connected to the angled bar mounted to have a vertical play upon said posts, as set 65 forth.

In testimony whereof I hereunto affix my signature in presence of two witnesses.

JOHN ALISON BUTTS.
